UNITED STATES PATENT OFFICE

154,928

DESIGN FOR A RING BOX OR THE LIKE

Melvin L. Kramer, Hoboken, N. J.

Application January 27, 1948, Serial No. 144,079

Term of patent 14 years

(Cl. D80—5)

To all whom it may concern:

Be it known that I, Melvin L. Kramer, a citizen of the United States, residing at Hoboken, in the county of Hudson and State of New Jersey, have invented a new, original, and ornamental Design for a Ring Box or the like, of which the following is a specification, reference being had to the accompanying drawing, forming part thereof.

Fig. 2 is a similar view thereof as it appears in open position.

The back of the ring box is plain and the side thereof not shown corresponds in appearance to the side illustrated.

The essential features of my design reside in the portions shown in solid lines.

I claim:

The ornamental design for a ring box or the like, as shown and described.

MELVIN L. KRAMER.
